(57) **CLAIM**

I claim the ornamental design for a fire suppression system tank bracket, as shown and described.

DESCRIPTION

FIG. 1 is a bottom front perspective view of a fire suppression system tank bracket showing my new design;

FIG. 2 is a top rear perspective view of the device shown in FIG. 1;

FIG. 3 is a top front perspective view of the device shown in FIG. 1; and,

FIG. 4 is a side perspective view of a portion of the device shown in FIG. 1.

1 Claim, 4 Drawing Sheets

FIG. 1

FIG. 2

FIG. 3

FIG. 4
